LEAKPROOF CARTON

Edwin C. Siewert, Wausau, Wis., assignor to
Marathon Corporation, a corporation of Wisconsin

Application March 13, 1944, Serial No. 526,206

2 Claims. (Cl. 229—16)

This invention relates to a paper carton that is leakproof at the bottom corners.

Many attempts have been made previously to construct paper cartons that can be filled with fluid contents without leaking at the bottom corners or seams. Such prior attempts are exemplified by Patents Nos. 1,950,934, March 13, 1934, and 1,973,633, September 11, 1934. In such carton constructions there is a tendency for the liquid in the carton to work its way between the overlapped side walls and thus leak out of the carton. In the construction shown in Patent No. 1,950,934 it is not possible to glue the overlapped side panels throughout their entire area as there is an interposed bottom flap of smaller area than the overlapped side panels so that in actual machine production an unglued channel is always left above the interposed bottom flaps through which the liquid will work its way through to the outside of the carton. Likewise in the carton construction shown in Patent No. 1,973,633, the liquid tends to work through between the abutting edges of the inner flaps interposed between the overlapped side walls.

The disadvantages of such prior constructions are overcome by the present invention by providing a leakproof construction as will be apparent from the following specification and drawings wherein:

Figure 1 is a plan view of the outer face of the paper blank from which the carton is made.

Figure 2 is a plan view of the inner face of the blank.

Figure 3 is a perspective view of the completed carton made from the blank shown in Figure 1.

Figure 4 is a perspective view of the partially completed carton.

Figure 5 is a perspective view of the completed carton partially broken away.

Figure 6 is a fragmental perspective view of the lower portion of the carton.

Figure 7 is a plan view of Figure 6 partly broken away, and

Figure 8 is a fragmental sectional view of the carton filled with a liquid.

Referring to the drawings the carton is constructed from an integral blank shown in Figures 1 and 2 made of paper, cardboard and the like. The blank is suitably scored along lines 1, 2, 3, 4, 7, 8, 9, 30, 31 and 32 to form a bottom wall 14, a front wall 18 and a rear wall 16. Side panels 11 and 12 are hinged to rear wall 16 along scored lines 1 and 2, respectively. Side panels 17 and 19 are hinged to front wall 18 along score lines 30 and 31, respectively. Triangular shaped

bottom flaps 15 are hinged to bottom wall 14 along score lines 7 and 8, respectively. The flaps 15 are separated from adjacent side panels 11 and 12 by cut score lines 42, respectively, and by cut scores 55 and 56 from adjacent side panels 19 and 17, respectively. Closure flap 22 is hinged to side panel 12 along score line 6. Closure flap 20 is hinged to side panel 11 along score line 5. The sides 60 and 65 of closure flap 20 and sides 57 and 61 of closure flap 22 are cut so as not to extend beyond the side walls of the carton when the flaps are overlapped in the position shown in Figure 5. The length flap 22 is of such dimension that the free edge 62 will not extend beyond the wall of the carton when the flap is folded to close the carton, as shown in Figure 5. Flap 22 is preferably of such dimension as to fully close the open end of the carton. Closure flap 23 is hinged to front wall 18 along score line 32. This flap is provided with a locking tongue 24. Closure flap 21 is hinged to rear wall 16 along score line 3. Flap 21 is cut to such dimensions that the free edges 58, 59 and 63 do not extend beyond the walls of the carton in closed position as shown in Figure 3. This flap is provided with a slit 25 for receiving tongue 24 in locking engagement.

In forming the carton from the blank previously described, adhesive is applied to the outer surfaces of side panels 17 and 19 and triangular flaps 15 as shown in Figure 1. The bottom flap 15, front wall 18 and rear wall 16 are folded upright in perpendicular relation to the bottom wall 14 as shown in Figure 4. At the same time side panels 17 and 19 are then folded at right angles to the front wall 18 and triangular bottom flaps 15 are then brought into contact with the outer faces of side panels 17 and 19 and adhered thereto throughout their contacting areas. Adhesive is then applied to the inner faces of side panels 11 and 12. Side panels 11 and 12 are then folded against the adjacent side panels 17 and 19 and adhered thereto and the superimposed adhered bottom flap 15 throughout their contacting areas to form the completed carton. After the contents are placed in the carton the open end is closed by folding over inner closure flaps 20 and 22 in overlapped relation as shown in Figure 5 and then folding over outer closure flaps 21 and 23 in overlapped relation. Tongue 24 of flap 23 is then inserted into slit 25 to lock the outer closure flaps as shown in Figure 3.

In the completed construction of the carton it will be noted that the bottom flaps 15 are adhered and firmly retained between the over-

lapped side panels 11 and 17, and 12 and 18, respectively, throughout their entire area. The contacting face portions of the side panels are also adhered throughout their entire area so that no unglued pocket portions exist anywhere at the overlapped side panels.

Triangular bottom flaps 15 are cut at 42 to facilitate the folding operation during machine production of the carton. A shoulder portion 43 is provided to ensure against leakage at the corners of the carton at the exposed edges 49 and 50 of the side panels 11 and 12, respectively. It will be noted that the bottom flaps 15 are substantially triangular in shape and their extreme tip portions 70 extend to the top edges 45 and 46 of the carton. By virtue of this construction leakage of any liquid contents A is obviated so that the carton is leakproof. If any leakage of contents A should occur say between side panels 11 and 17 the liquid may travel up to the edge 40 of bottom flap 15, but cannot travel past this line as the glued flap 15 will act as a dam and prevent any liquid from travelling outwardly toward the free edge 49 of side panel 11 where it could leak out of the carton. It is thus evident that whether the carton is full or partially filled with liquid contents the triangular flaps 15 serve as an effective dam to prevent any escape of the liquid through the seams of the carton.

Although it is preferred to use triangular shaped bottom flaps 15, it is obvious that any other suitable shape of bottom flaps 15 can be utilized provided the flaps extend to the top of the carton to serve as a dam for any liquid escaping between the side panels as previously explained.

The present construction provides a very effective leakproof carton construction. When

cartons made of paper or cardboard are filled with water or other liquids no leakage whatsoever will occur. The present invention thus provides a very satisfactory carton that has many uses for packaging ice cream, lard and other substances that are initially in liquid form and are then congealed for storage and shipment.

Having thus described the novel and essential features of my invention, I claim:

1. A carton formed from a single integral blank comprising a bottom wall, opposed front and rear walls hinged to said bottom wall, side panels hinged to said front and rear walls, said side panels being substantially coextensive in area, substantially triangular shaped bottom flaps hinged to said bottom wall, said side panels being adhered in overlapped relation with the bottom flaps adhered therebetween throughout the contacting faces thereof, the apex of said triangular bottom flaps extending substantially to the upper edge of said overlapped side panels to provide a substantially leakproof carton.
2. A downwardly tapered carton formed from a single integral blank comprising a bottom wall, opposed downwardly tapered front and rear walls hinged to said bottom wall, downwardly tapered side panels hinged to said front and rear walls, said side panels being substantially coextensive in area, bottom flaps hinged to said bottom wall, said side panels being adhered in overlapped relation with the bottom flaps adhered therebetween throughout the contacting faces thereof, said bottom flaps tapering upwardly toward a point and extending substantially to the upper edge of said overlapped side panels to provide a substantially leakproof carton.

EDWIN C. SIEWERT.
